UNITED STATES PATENT OFFICE.

WILLIAM E. NICKERSON, OF CAMBRIDGE, MASSACHUSETTS.

ELECTRICAL SWITCH FOR ELEVATORS.

SPECIFICATION forming part of Letters Patent No. 404,015, dated May 28, 1889.

Application filed February 28, 1889. Serial No. 301,505. (No model.)

To all whom it may concern:

Be it known that I, WILLIAM EMERY NICKERSON, of Cambridge, in the county of Middlesex and State of Massachusetts, have invented certain new and useful Improvements in Electrical Switches for Elevators, of which the following, taken in connection with the accompanying drawings, is a specification.

My invention consists in combining with a hand-switch mechanism within the carriage of an elevator, electrically connected with the electrical devices by which the hoisting mechanism is controlled, fixed cam-pieces outside and independent of the elevator-carriage, arranged to operate the circuit-breaking devices within the car automatically, and thus cause the carriage to stop at the various landings when desired.

An application of my invention is shown in the accompanying drawings, in which—

Figure 1 is a view in elevation, showing sufficient portions of an elevator to enable one to understand the location and general arrangement of the parts that constitute my device. Fig. 2 shows the interior of the switch-box in elevation. Fig. 3 is a vertical section of the switch-box taken on the line *x* of Fig. 2, and Fig. 4 is a vertical section of the switch-box taken on the line *yy* of Fig. 2.

In the drawings, A, Fig. 1, represents the elevator-well, B the carriage, and C the hoisting-rope. Within the carriage B, I place a switch-box, D, which is connected to the various wires of the electric system.

E is a wire passing from the switch-box D through the tube M to the battery E'. Thence the circuit passes to the device E³, and returns to the switch-box through the wire H.

K is a wire leading from the switch-box D through the tube M to the motor H⁴, thence by the wire H³ to the battery H², the circuit being completed by the wires H' H to the switch-box D.

P P, Fig. 1, represent cam-pieces fixed to the well-room wall, which are so arranged that the elevator-carriage in its passage will cause the pin N' to come in contact with either of them. Then the said pin N' will be pushed inward and make a break in the circuit, the effect of which will be explained below.

My switch-box construction is shown in

Figs. 1, 2, and 3, and its interior devices are as follows: The wire or electrode H is connected by branches h h' to the contact-spring-plates N and L. The wire E passes to the switch-post E⁴, and the wire K to the switch-post K'. (See Fig. 2.) The contact-point N² is connected to the switch S at S' by the wire N³, and the contact-point L² is connected to the switch S at S' by the wire L³. The contact-spring-plate L is provided with a push-button, L', Fig. 4, its resilience tending to keep it out of contact with the point L²—that is, to keep the circuit open. On the contrary, the resilience of the contact-spring-plate N tends to keep it in contact with the contact-point N², only to be broken when the pin N' is forced inward by coming in contact with one of the cam-pieces P. (See Figs. 1 and 3.) The switch S is pivoted at S', Fig. 2, and can be turned to the right or left, as indicated by dotted lines, Fig. 2. When the switch S is vertical, both circuits are open.

In my device one of the devices—E³, for instance—is intended for the purpose of operating that part of the controlling mechanism of the hoisting-machine that causes the elevator-carriage to ascend, while the other acts upon the device for allowing the carriage to descend.

The operation of my invention is as follows: If it is desired to cause the elevator-carriage to go up, the switch S is turned to the left, so that the post E⁴ is connected through the switch and the wire N³, Fig. 2, to the contact N². Thence the circuit is made through the spring contact-plate N, wires H' H, device E³, wire E², battery E', wire E to post E⁴, and the circuit is complete, and will remain so until the carriage in its ascent causes the pin N' to come in contact with the cam-piece P, at which point it will be pushed inward and force the plate N from the contact-point N², thus breaking the circuit and causing the carriage to stop. To cause the carriage to again start upward, the switch S is left in its place and the plate L is forced by the push-button L', Fig. 4, down onto the contact-point L². This action substitutes a bridge (consisting of the wire L³, contact-point L², plate L, and wire h) for the portion cut out—viz., the wire N³, contact-point N², plate N, wire h'—and re-establishes the circuit through the device E³.

If the attendant holds the push-button L' down, the elevator-carriage will continue to ascend, irrespective of the action of the cam-pieces P and pin N'.

- 5 To cause the carriage to descend, the switch S is turned to the right and a circuit is established through the device H⁴ as follows: Starting from the battery H², the circuit passes through the wires H' H h', plate N, contact-point N², wire N³ to switch S; thence to switch-post K', wire K, device H⁴, and wire H³ to battery H². Now the circuit is complete and will remain so until the elevator-carriage in its descent causes the pin N' to come in contact 15 with one of the cam-pieces P, in which event the pin N' will push the contact-plate N away from the contact-point N², and thus break the circuit and stop the elevator-carriage.

To restore the circuit, the attendant has only 20 to force the push-button L' inward and a bridge will be made, as has already been set forth. To allow for the effect of the lateral movement of the carriage, due to looseness of fit in its ways on the action of the cams P, I so construct them that they will not press with a positive effect on the pin N', but with a pressure that will not force the pin so hard as to cause any injury or beyond a certain fixed distance—that is, after the pin N' has been 25 pressed in sufficiently to cause a separation of the contact-plate N and the point N²—then the pin will resist further motion and the cam-pieces will in turn yield, if required, by the lateral sway of the elevator-carriage. To 30 effect this, I make the cam-pieces P, as shown in Fig. 3, of a thin piece of spring plate metal and fasten one or both of its ends by means of screws *t*, which pass through slots made in the plate, so that it is free to yield to pressure.

40 I claim—

1. In an electric device for controlling the motion of an elevator-carriage, the combination of a series of cam-pieces on the walls of the elevator-well disposed with reference to the various landings and adapted to act upon 45 a circuit-breaking device within the carriage and cause the carriage to automatically stop at said landings and so remain until the circuit has been manually re-established, with electrical circuits having terminals within the 50 carriage connected to said circuit-breaking device, and an electric device adapted to actuate the controlling mechanism of the hoisting-engine, substantially as and for the purpose set forth.

2. In an electric device for controlling the motion of an elevator-carriage, the combination of the cams P P and a circuit-breaking device, as described, with an electric bridge adapted to re-establish the electric circuit at 60 the option of the attendant when said circuit has been automatically broken at a landing by a fixed cam - piece, substantially as described, and for the purpose set forth.

3. In an electric device for controlling the 65 motion of an elevator-carriage, the combination of the switch S, posts E⁴ K', contact-points N² L², contact-plates N L, and the several connecting and circuit wires, with an electric device, substantially as and for the purpose set 70 forth.

In testimony whereof I have signed my name to this specification, in the presence of two subscribing witnesses, on this 26th day of February, A. D. 1889.

WILLIAM E. NICKERSON.
